To all whom it may concern:

Be it known that I, Henry Dreyfuss, a citizen
of the United States, residing at New York city,
in the county of New York and State of New York,
have invented a new, original, and ornamental
Design for a Weighing Scale, of which the fol-
lowing is a specification, reference being had to
the accompanying drawing, forming part thereof.

In the drawing, the figure is a perspective view

of a weighing scale, showing my new design;
the opposite side of the weighing scale presents
substantially the same appearance as the side
shown, and the back is plain.

I claim:

The ornamental design for a weighing scale,
as shown and described.
